UNITED STATES PATENT OFFICE.

EUGÈNE SCHNEIDER, OF LE CREUZOT, FRANCE, ASSIGNOR TO SCHNEIDER & CIE, OF PARIS, FRANCE, A LIMITED JOINT-STOCK COMPANY OF FRANCE.

FIELD-GUN CARRIAGE.

1,311,777.

Specification of Letters Patent. Patented July 29, 1919.

Application filed July 3, 1916. Serial No. 107,392.

To all whom it may concern:

Be it known that I, EUGÈNE SCHNEIDER, a citizen of the Republic of France, residing at Le Creuzot, France, have invented a new and useful Improvement in Field-Gun Carriages, which is fully set forth in the following specification.

The present invention relates to improvements in gun carriages and more particularly to gun carriages in which there is a gun-supporting frame mounted to rotate about a vertical axis on a lower carriage frame, and has for its object to provide gun carriages of this type with means for directing the fire of the gun with reference to fixed base lines or points or for indirect aiming, thereby avoiding the necessity of taking a fresh sight for firing at any predetermined target within a given sector of horizontal range.

The above object is accomplished by providing a gun carriage having an upper gun-supporting frame mounted to turn on a lower carriage frame with a sighting device (hereafter termed an indirect sighting device) which is mounted on a movable frame which may be the lower carriage frame carrying with it the upper gun-supporting frame or a special frame movable with the upper gun-supporting frame. For indirect sighting the sighting device is mounted on the lower carriage frame and is sighted on a distant object along a line passing through the virtual vertical axis of rotation of the upper carriage frame. This line becomes a base line or an auxiliary sighting line on which the indirect sighting device is to be maintained during firing at any particular target. With this arrangement, a directing line of sight is selected making any predetermined angle with the base line and passing through the axis of rotation of the upper gun-supporting frame. When the indirect sighting device is mounted on the lower carriage frame, this directing line of sight preferably passes through the zero point of the gun training arc mounted on the lower carriage frame. When the indirect sighting device is mounted on a separate movable frame, the directing line of sight may pass through any predetermined fixed point such as a distant sighting point.

Before firing at given objects, the angle subtended between the base line or auxiliary sighting line and the line passing

through each object and the axis of rotation of the upper gun carriage frame is previously determined by a theodolite or other suitable angle-measuring device. This angle algebraically added to the fixed angle between the base line and the directing line of sight gives the angle on the firing scale mounted, for example, on the lower carriage frame which is to guide the gunner in indirect aiming. Thereafter firing is effected without taking fresh aim for each object. The gun is aimed by training its longitudinal axis through the predetermined angle for indirect aiming.

Any deviations from the correct training line that may be caused by the firing are corrected by bringing the auxiliary sighting line back to its original position by means of adjusting mechanism adapted to restore the sighting device support or frame to its original position and may act to restore the lower carriage frame to this position in which case the mechanism is located to act on the gun trail, or it may act to move a separate support for the sighting device in which case it is mounted on the lower carriage frame as shown in Figures 6 and 7.

In order that the invention may be more readily understood, reference is had, by way of example, to the accompanying drawings which show two constructional forms of the invention. These drawings are intended to assist the description but not to define the limits thereof.

In said drawings

Fig. 1 is a diagram illustrating the use of a field gun carriage constructed according to this invention;

Figs. 2 to 5 illustrate one example of construction of the improved gun carriage;

Fig. 2 being a side elevation,

Fig. 3 a plan,

Fig. 4 a vertical longitudinal section on the line IV—IV of Fig. 3, and

Fig. 5 a cross section on the line V—V of Fig. 3, showing a detail.

Figs. 6 and 7 are respectively a side elevation partly in vertical section, and a plan, partly in horizontal section, of a second example of construction of the improved field gun carriage constructed as to provide independency between the line of sight and the horizontal displacements of the gun.

Referring first to Figs. 1 to 5, A is a slide or cradle on which the gun barrel is

mounted so as to be capable of sliding longitudinally therein. The cradle A is journaled on trunnions in the upper mounting B—B¹—B of fork or stirrup shape, whose 5 semi-circular base B¹ is adapted to revolve about a virtual vertical axis O on a concentric guide C¹ of the lower carriage C—C¹—C. This lower carriage comprises a curved axle D having its center of curvature in an imaginary vertical axis O which is the common 10 center of the base B¹ of the upper mounting and of the guide C¹.

The upper mounting B—B¹—B in pivoting about its imaginary axis O, bears in 15 front upon the curved axle D, and at the rear upon the guide C¹ formed on the head of the lower carriage C—C¹—C with which the carriage trail C² forms one piece.

According to this invention the upper 20 mounting is provided with a bracket E, and the lower carriage is provided with a bracket F; both brackets being designed to support one and the same sighting apparatus G which can be placed at will upon the 25 bracket F as indicated in full lines in Fig. 2, or upon the bracket E as indicated in dash and dot lines in the same figure.

In the example shown, the lower carriage C—C¹—C²—C is adapted to be adjusted 30 transversely along the anchoring plate H by any suitable mechanism, for instance such as is illustrated in Figs. 3, 4 and 5. This adjustment allows of correcting deviations from the line of aim due to successive firing.

35 This mechanism comprises a worm I journaled in the trail C² and adapted to move along a rack J on the anchoring plate H. A bevel pinion i fixed to the worm I engages a pinion K which is driven by means 40 of a removable hand-wheel N through gearing L—M—m—n. By means of this adjustment, any deviations from the correct training line that may be caused by the firing are corrected by bringing the sighting 45 line back upon the given sighting point such as Z.

The training mechanism for the upper gun-carriage mounting B—B¹—B comprises a hand-wheel P fixed on a shaft p journaled 50 in the upper mounting which actuates, through gearing p'—p²—p³—p⁴—p⁵—p⁶, a pinion Q fixed on a vertical axle q journaled in the upper mounting. Q is a pinion carried by the upper mounting and engages 55 circular rack d formed on the curved axle D, the upper side of which carries a graduated scale from which the various training angles can be read (Fig. 3).

The device thus far described operates as 60 follows:

The lower carriage having been brought into position and anchored at the point x (Fig. 1) so as to cover a sector O—X—x¹—X—O, then indirect firing is aimed upon 65 any given target Y situated at any point of

the sector, by placing the sighting apparatus G on the bracket F of the lower carriage, and training the gun by sighting continuously any given auxiliary sighting point Z along the line O—Z, which incloses a constant angle α with a fixed directing line such as the line O—x¹ bisecting the angle subtended by the arc X—x¹—X. The angular relations of the lines of sight of the targets Y, Y¹, Y² to the base line O—Z are 70 previously measured by any suitable means, and the values α —B, α —B¹, α —B² which give the angular displacement of these lines of sight with the fixed directing line of sight determined. The upper mounting B—B¹—B 80 is now successively trained by operating training wheel P about axis O on the lower carriage as indicated by the values α —B, α —B¹, and α —B². The angle of fire required to hit targets Y, Y¹, Y² is thus obtained indirectly without the necessity of taking a fresh sight for firing as the target is changed.

Should the firing cause a deviation from the correct training line, this error is corrected by adjusting the lower carriage trail across its anchoring-spade plate H.

If now it is desired to change from indirect aiming to direct aiming, as for instance, at an aerial target, the sighting apparatus G is transferred from the bracket F to the bracket E. The training that has been performed by the right-hand man will now be performed by the left-hand man who therefore now serves the sighting apparatus, 90 the removable handwheel N being transferred for this purpose into the position N¹ indicated in dash and dot lines in Fig. 3, wherein it allows of actuating gearing r, r¹, r², r³, r⁴; the pinion r⁴ engaging the pinion 95 p⁵ at a point diametrically opposite the pinion p⁴.

In the modification illustrated in Figs. 6 and 7, the bracket F for supporting the one and only sighting apparatus G for indirect firing, instead of being mounted on the lower carriage C—C¹—C, is carried by an arm S fixed by means of a stud screw s to a circular rack T which is concentric to and movable in the curved axle D. The circular rack T has two series of rack teeth, namely, internal teeth t engaged by the pinion Q of the upper mounting, and external teeth t¹. By means of the external teeth t¹ the circular rack T with the arm S 110 and the bracket F can be shifted along the hollow axle around the imaginary axis of pivotatation O, for instance by means of the gearing comprising the removable handwheel N which is mounted on an axle U 115 journaled in the lower carriage side frame C, and drives through the gearing u, u¹, u², u³, a pinion v¹ fixed on an axle v which carries a worm V engaging the external teeth t¹, and journaled in a bracket bearing 120 125 130

V¹ attached to or formed on the curved axle D. In following the movements of the circular rack T, the stud s moves in a slot d¹ formed in the curved axle.

5 It will be readily perceived that the motion imparted by the hand-wheel N to the circular rack T, will be transmitted through the internal teeth t to the pinion Q which is rendered stationary by any suitable known 10 automatic jamming device not shown, and consequently to the entire structure constituted by the upper mounting and the gun barrel carried by the latter.

The training movements imparted by the 15 hand-wheel P will in no way affect the position of the circular rack T, nor that of the bracket F for the sighting apparatus. The arrangement thus provides also a sighting means having an independent line of 20 sight in the horizontal plane.

What is claimed is:—

1. In combination, a field gun carriage comprising an upper gun-supporting frame and a lower carriage frame on which said 25 upper frame is adapted to train about a virtual vertical axis in a horizontal plane of said carriage frame, and a sighting device supported on said carriage frame and having its line of sight passing through said 30 axis, and means for keeping the sight of said sighting device set along a predetermined base or auxiliary sighting line through said axis for indirect aiming of the gun in reference to said base line.

35 2. In combination with a field gun carriage comprising an upper gun-supporting frame and a lower carriage frame on which said upper frame is adapted to train in a horizontal plane about a virtual vertical axis 40 within said carriage frame, a sighting device supported on said lower frame and having its line of sight passing through said axis, and means for keeping the sight of said device set along a predetermined base line or 45 auxiliary sighting line through said axis for indirect aiming of the gun.

3. In combination with a field gun carriage comprising an upper gun-supporting

frame and a lower carriage frame on which said upper frame is adapted to train in a 50 horizontal plane about a virtual vertical axis within said carriage frame, a sighting device adapted to be interchangeably supported on either frame, said device when supported on the lower frame having its 55 line of sight passing through said axis, and means for moving said lower frame to keep the sight of said device set along a predetermined base line or auxiliary sighting line passing through said axis for indirect aiming of the gun. 60

4. In a field gun carriage, the combination of an upper gun-supporting frame the rear portion of which is struck on an arc, a lower carriage frame having a curved axle 65 portion provided with a training arc and adapted to adjustably support the forward portion of said upper frame and a rear arc portion on which said upper frame rests, said arc portions having a common center, 70 a sighting device adapted to be interchangeably supported on either frame, said device when supported on the lower frame having its line of sight passing through said common center, and means for moving said 75 lower frame to keep the sight of said device when mounted thereon set along a predetermined base line or auxiliary sighting line passing through said center for indirect firing of the gun. 80

5. A field gun carriage as claimed in claim 3 wherein the means for moving the lower frame for correcting deviations of the line of sight of the sighting device from the auxiliary sighting line through said axis 85 comprises means for training the gun trail of the lower gun carriage about a fixed anchoring point of the trail.

In testimony whereof I have signed this specification in the presence of two subscribing witnesses. 90
